PILOT CONTROLLED GAS VALVE

Filed Dec. 14, 1925

UNITED STATES PATENT OFFICE

EDGAR J. LEACH, OF JANESVILLE, WISCONSIN, ASSIGNOR TO TIME-O-STAT CONTROLS COMPANY, OF ELKHART, INDIANA, A CORPORATION OF MARYLAND

PILOT-CONTROLLED GAS VALVE

Application filed December 14, 1925. Serial No. 75,462.

This invention relates to an automatic valve control for the gas line carrying gaseous fuel to burners which is designed to automatically shut off the gas supply in the event that the pilot light which is used to light the main burner, and which should burn continuously, becomes extinguished. Gaseous fuel burners ordinarily have a pilot light, so-called, associated therewith, located in close proximity to the burner so as to light the same when the fuel is supplied to the burner. As long as this pilot light is burning there is no danger from escape of gas, as the burner will always be lighted if the pilot is burning and gas will not escape through the burner. Many times the light becomes extinguished due to various causes, and when thus extinguished the fuel which is supplied to the main burner is wasted or escapes into the room in which the burner is located and, the room soon becomes filled with gaseous fuel which is a source of great danger not only to persons entering the room who are liable to be overcome and asphyxiated, but also by reason of the explosive mixture made by the mixing of fuel with the air of the room so that if a match is lighted in the room a severe explosion is very likely to occur.

It is a primary object and purpose of the present invention to provide an automatic control for a valve which will effect the release of the valve so as to positively close the passage of gas to the main burner in the event that the pilot light is extinguished. This closing of the valve and consequent cutting off of fuel occurs a short time after the pilot light is extinguished and before gas escaping into the room becomes in any way dangerous. A further object of the invention is to provide a device of this character which is relatively simple in construction and is easily installed, is durable and efficient in operation and is not liable to get out of order so as to become ineffective for the purposes for which it is designed.

To these ends I have devised the construction and arrangements of parts described in the following description and fully shown in the accompanying drawing, in which

Fig. 1 is an elevation of the apparatus of my invention, the valve which is controlled thereby being shown in section,

Fig. 2 is a fragmentary vertical section through one element of the construction, the view in Fig. 2 being somewhat enlarged, and

Fig. 3 is a fragmentary elevation with parts in section illustrative of a slightly different form of heat transfer element which forms one of the essential features of the invention.

Like reference characters refer to like parts in the different figures of the drawing.

In the construction shown, the burner 1 may be of any desired and conventional type used for burning gaseous fuel, the fuel being supplied thereto through suitable pipes 2. A valve 3 which may be either automatically or manually controlled is located in said pipe adjacent the burner which may be turned to either open the passage to supply fuel to the burner or close the same to extinguish the burner. A short branch pipe 4 is connected with the main gas line 2 at any desired point and at its upper end is equipped with a nozzle 5 which allows the escape of a limited quantity of gas only, and it is designed that this gas which escapes shall be burned continuously, thus making the pilot light which, being located closely adjacent to one side of the burner, will light the fuel when it escapes through the burner.

In the main gas line 2 a valve casing 6 is located having the usual dividing partition 7 with an opening and valve seat therein, the valve 8 in its closed position seating against the valve seat and stopping the passage of any fuel through the line 2, and a rod 9 is connected with the valve 8 and passes through the opening in the partition 7 and outwardly through a threaded neck 6^a integrally formed with the casing 6. A coiled compression spring 10 is located between a side of the casing 6 and valve 8, the tendency of which is to move the valve to closed position when it is free to do so. Whenever the valve is in open position, as shown in Fig. 1, the spring is compressed as is apparent.

Conveniently mounted on the stem 6^a is a supporting bracket of substantially U-shape, 100

having vertical legs 11 and 13 connected by base 12, the leg 11 having an opening so that it fits over the stem 6^a and being threaded for application of a suitable binding nut as shown. An arm 14 extends horizontally from the upper portion of the leg 11 above the valve rod 9 and the stem 6^a through which it passes. A lever 15 is pivotally mounted between its ends on the outer end of the arm 14 being formed with a downwardly extending finger 16 at its lower end which bears against the projecting end of the rod 9. Member 15 is also formed with a dog 17 which extends substantially horizontal from the member near the pivot connecting it to the arm 14.

The base 12 of the supporting bracket at its upper side carries ears 18 between which a bar 19 is placed and to which said bar is pivotally connected at its lower end. The upper end of the bar 19 is formed with a hook 20 adapted to engage with the dog 17 and, when thus engaged, hold the lever 15 in the position shown in Fig. 1 and thereby maintain the valve 8 in its open position. A coiled spring 21 is connected at one end to the upper end of the bar 19 and at its other end has connection with an adjusting screw 22 which is threaded through the leg 13 of the supporting bracket. Spring 21 is under tension and normally when free to do so will pull the bar 19 away from the lever 15 and disengage the hook 20 from the dog 17, this freeing the valve 8 so that it may move to closed position under the influence of the spring 10.

A longitudinal, expandable and contractible corrugated metal bellows 23 having closed ends, is mounted at one end on the leg 13 of the supporting bracket and at its opposite end is equipped with a conical projection 24, the end of which fits in a suitable notch in the member 19 a short distance above its lower end. A tube 25 is connected with the bellows and leads to a bulb 26 with which it is connected, the bulb, tube and bellows being closed and air tight, and being charged with a suitable fluid having a high co-efficient of expansion so that it readily expands and contracts with changes of temperature. The bulb 26 in the construction shown is located above, connected with the casing surrounding the burner. The means of supporting the bulb, however, is of no essential importance in this invention and it may be supported in any desired manner. While a bellows is shown and described and in practice is preferred, any equivalent expandible element may be used so long as it will expand the necessary small amount required in the operation of the device.

A metal ribbon 28 is formed with a loop 29 which surrounds and closely embraces the bulb 26, the end of the ribbon being located directly over the nozzle 5 for the pilot light so that the burning pilot serves to heat this

ribbon and heat is transmitted through it to the bulb 26, causing an expansion of the fluid therein and consequent elongation of the bellows 23 which overcomes the spring 21 and holds the hook bar 19 in operative engagement with the dog 17, it being apparent that the expansion of the bellows 23 is maintained continuously at all times when the pilot light is burning.

If for any reason the pilot light should be extinguished, it is apparent that the ribbon 28 will immediately cool and there will be a consequent contraction of the fluid within the bulb 26, pipe 25 and bellows 23, resulting in the longitudinal contraction of the bellows 23 so that spring 21 may draw the hook 20 on the bar 19 out of engagement with the dog 17, whereupon valve 8 moves to closing position and no fuel can pass to the burner or burners and escape therefrom. This will occur a short time after the pilot light has become extinguished and before there has been an escape of sufficient fuel such that it will have any detrimental effect.

In Fig. 3 a somewhat different, and in many respects, a preferred form of construction is shown for conveying heat from the pilot light to the bulb which contains the expandible fluid. In the construction shown in Fig. 3 the ribbon 28 is replaced by a rod 30 or relatively large cross section which, adjacent the bulb, is materially reduced in cross section to make the part 31 which passes into the bulb and is equipped with a disc 32 within the bulb as shown. The rod 30, its extension 31 and the disc 32, are preferably of copper. Said rod 30, being of relatively large cross section, has a large capacity for and will absorb all of the heat that is liable to be given to it from its contact with the pilot light or its adjacency to the main burner. The smaller rod 31, because of its small cross section, will not have the capacity for conducting heat that the larger rod 30 has, so that a limited quantity only of the heat absorbed by the larger rod 30 will be conveyed to the bulb 26. This insures that damage to the bulb, because of conduction to it of too great a quantity of heat, will not occur. In addition this construction is of value where, in certain installations, the bulb 26 is located a considerable distance from the burners. In such case the larger rod 30 capable of absorbing and conducting a large quantity of heat, will carry heat the necessary distance and transmit it to the bulb through the reduced section 31; and the rod 30, in effect, will serve as a reservoir for heat so that a sufficient quantity will always be ready for conduction through the reduced section 31 to the bulb 26 at all times when the pilot light is burning.

This has been proven by extensive experiments and trials and the construction shown in Fig. 3 has proven especially satisfactory in

those installations where the bulb 26 must be located at a distance from the pilot light. The construction shown and described is simple, being very efficient and practical and is an insurance against the detrimental escape of quantities of gaseous fuel in the event of extinguishment of the pilot light used in connection with gaseous fuel burners. Many variations in detail of construction are possible with this invention and accordingly I do not limit the invention to the exact details shown and described, but consider it comprehensive of all forms of structure coming within the scope of the appended claims defining the invention.

I claim:

1. In an apparatus of the character described, a burner, a valve for controlling the passage of fuel to the burner, spring means normally tending to close the valve, manually operable means for moving the valve to open position, a latch engaging with the manually operable means to thereby retain the valve in open position, an expansible and contractible element having a fixed support at one end and bearing at its opposite end against the latch to hold the latch in operative position, spring means acting on the latch against said element to disengage the latch from said manually operable means on contraction of the element, a tube leading from said element, a bulb with which the opposite end of the tube is connected, said bulb, element and tube being charged with a fluid which expands on rises of temperature, and means whereby heat may be transferred from the burner to said bulb while the burner is in operation.
2. In apparatus of the character described, a burner, a valve for controlling the supply of fuel to said burner, a closed bulb, means for heating said bulb from the burner, a tube leading from the bulb, a fixed support, an expansible and contractible element fixed at one end on said support, said tube being connected with said end of the element, spring means acting to normally close the valve, a manually operable member for opening the valve, and a latch to engage with and hold said member in operative position against which latch the other end of said bellows bears to hold the latch in operative position at all times that the element is expanded, said element contracting and releasing the latch when the burner is extinguished.
3. In combination, a burner, a conduit for carrying fuel to said burner, a valve casing mounted in the conduit, a valve within the casing, a valve rod extending from the valve through one side of the casing, spring means tending to move the valve to stop the passage of fuel to the burners and project the free end of said rod outwardly, a support, a lever pivotally mounted between its ends on said support having one end engaged with the outer end of said valve rod, said lever being formed with a laterally projected dog, a latch member pivotally mounted on the support and formed with a hook to engage said dog when the lever is moved to open the valve, a spring disposed between the latch member and support normally acting to draw the latch member away from said dog, an expansible and contractible element attached at one end to the support and at its opposite end bearing against the latch member, said element when expanded, moving the latch member to position to engage with said dog, a tube extending from the element, a bulb to which the opposite end of the tube is connected and a heat conducting member associated at one end with said bulb and at its opposite end lying in close proximity to the burner so as to be heated thereby, substantially as and for the purposes described.
4. In a fuel conduit for conducting gaseous fuel, a valve casing, a movable valve therein for controlling the passage of fuel through the conduit, means normally closing the valve, manually operable means for opening the valve, a latch to engage with the manually operable means and hold the valve in open position, means normally tending to move the latch means to disengaging position, thermostatically expansible and contractible means engaging with the latch means to hold it in operative position, whenever said expansible means is expanded, a tube connected with said expansible means, a bulb connected with the opposite end of the tube, said bulb, tube and expansible means being charged with a fluid readily expansible on increases of temperature, a burner supplied with fuel from said conduit, and a member of metal capable of conducting heat disposed with one end in position to be heated by said burner and with the opposite end disposed in association with said bulb to thereby supply heat to the bulb to expand the material therein and thereby expand said expansible means substantially described.
5. In an apparatus in character described, a burner, a valve for controlling fuel supply to said burner, a thermostatic bulb adapted to receive heat from said burner, an expansible and contractible element, a tube connecting the bulb and element, means normally closing the valve, manually operable means for opening the valve, a latch to engage and hold the manually operable means in operative position, said latch being held by said element, when the burner is burning, in position to engage with said manually operative means, a rod of metal of relatively large diameter located with one end disposed to be heated by the pilot burner, said rod at its opposite end being reduced in diameter and associated with said bulb to heat the same substantially described.
6. In an apparatus in character described,

a burner, a valve for controlling fuel supply to said burner, a thermostatic bulb adapted to receive heat from said burner, an expandible and contractible element, a tube connecting the bulb and element, means normally closing the valve, manually operable means for opening the valve, a latch to engage and hold the manually operable means in operative position, said latch being held by said element, when the burner is burning, in position to engage with said manually operative means, an elongated member of metal having a relatively large cross section and having one end disposed in the flame of the pilot 15 burner, and at its opposite end being reduced in cross section area and associated with said bulb to heat the same substantially described.

7. In an apparatus of the character described, a burner, a bulb, a heat conducting 20 member having one end associated with said burner to be heated thereby and having its other end extending into said bulb, an enlarged heat radiating member upon the inner end of said conducting member within 25 said bulb, and means associated with the bulb for actuating a valve, said means being actuated by expansion and contraction of fluid within the bulb.

8. In an apparatus of the character described, a bulb, a burner, a heat conducting 30 element having a relatively large portion associated with the burner and heated thereby, and a relatively small portion extending between the large portion and the bulb and associated with the bulb to heat the same by 35 conduction, and means associated with the bulb to actuate a valve, said means being actuated by expansion and contraction of fluid in the bulb.

40 In testimony whereof I affix my signature.
